ADSORPTION APPARATUS AND METHOD

William E. Moore, Pittsburgh, and George L. Simpson, Coraopolis, Pa., assignors to Pittsburgh Research Corporation, Pittsburgh, Pa.

Application February 14, 1936, Serial No. 63,966

10 Claims. (Cl. 183—4)

This invention relates to improvements in adsorption apparatus of the type such as used for the conditioning of air, gas or other fluid, and is particularly well adapted for the drying or dehumidification of air or gas, although not necessarily restricted to this use.

An important use to which the present invention is applicable is the removal or reduction of the moisture content of air in rooms or houses, or in the treatment or conditioning of air or gas for industrial purposes.

An object of the present invention is to provide an apparatus of this character which will handle a large volume of air, gas or other fluid and remove moisture or other impurities therefrom.

Another object of this invention is the provision of a device of the above mentioned character which is continuous and automatic in operation, and which will give a continuous and uninterrupted flow of dried air or gas.

A further object of the invention is to provide a device of this character which is of simple and compact construction, which is inexpensive to construct and operate, and which is efficient and certain in operation.

Other objects and advantages of the invention will be apparent during the course of the following description.

30 In the accompanying drawings which form a part of this specification and wherein like characters of reference denote like parts throughout,

Figure 1 is a vertical longitudinal sectional view through an apparatus embodying this invention. Figure 2 is a horizontal sectional view taken on the line 2—2 of Figure 1.

Figure 3 is a similar view taken on the line 3—3 of Figure 1.

Figure 4 is a vertical transverse sectional view taken on the line 4—4 of Figure 1.

Figure 5 is a horizontal sectional view through the valve and valve casing on the line 5—5 of Figure 1, looking in the direction of the arrows.

Figure 6 is a similar view taken on the line 6—6 of Figure 1, and,

Figure 7 is a side elevation of the valve removed from its casing.

In the drawings, wherein for the purpose of illustration is shown a preferred embodiment of the invention, the numeral 10 designates the casing of this apparatus which is of metal and of generally rectangular shape, open at its top. An adsorbing unit is preferably removably arranged in the upper portion of the casing and rests on suitable brackets 12 secured to the interior of

the casing. The adsorbent unit or container consists of upper and lower plates or covers 13, which may be lined with suitable insulating material 14, spaced apart by means of side wall plates 15 and secured together by suitable bolts 5 or tie rods 16. The side wall plates 15 are spaced from the walls of the casing 10 and this space is filled with a layer 17 of suitable heat insulating material. The layer 17 is preferably carried by the adsorbent unit so as to be removable 10 therewith, although it may obviously be secured to the casing 10 if desired.

Central openings are provided in the covers or plates 13 to receive a cylindrical valve casing or sleeve 18 which extends through the adsorber unit and above and below the same. The valve sleeve 18 is of large diameter and is secured in the adsorber unit by means of suitable split clamping rings 19 welded or otherwise secured to the cover plates 13 throughout a portion of 20 their circumference. Valve sleeve 18 is vertically arranged at the center of the adsorber unit and casing 10.

A relatively thick horizontal layer of adsorbent material 20 is spaced equally from top and bottom cover plates 13 and extends from the side walls 15 of the adsorber unit to the valve sleeve 18, completely dividing the space within the adsorber unit. Fine mesh wire screen 21 covers the top and bottom of the layer of adsorbent to hold the 30 adsorbent material together, and a heavy screen 22 of larger mesh is arranged above and below the layer of adsorbent and welded to the side walls 15 and valve sleeve 18 to secure the layer of adsorbent in position.

35 It will be seen that the layer 20 of adsorbent material, which may be any suitable material such as alumina or the like, divides the adsorbent unit into an upper chamber 23 and a lower chamber 24. Suitable vertical metal partitions 25 extend between the cover plates 13 and between the side walls 15 and valve sleeve 18 to divide the adsorber unit and adsorbent bed into sectors of equal area, as indicated in Figure 3. The sectors are shown as eight in number, for convenience of illustration, but may obviously be of any number desired.

An exhaust chamber 26 is formed by an inverted metal cover 27 secured to the outer edges of the lower plate 13 and extends the length and 50 width of the adsorber unit, surrounding the lower end of the valve sleeve 18 which terminates immediately below the inverted cover 27.

The open top of casing 10 is normally closed by a relatively deep cover section 28 which is 55

provided with suitable clips or flanges 29 or other fastening means to removably secure the cover section to the casing and form an air tight joint. A centrally arranged conduit 30 extends down into the cover section centrally thereof and fits snugly around the upper end of valve sleeve 18. A heater 31 is arranged in the conduit 30 to heat air for reactivating the adsorbent, and may be of any suitable type, such as an electrical resistance heater, a gas, steam or oil heater. The top of cover section 28 is lined on its under side with suitable heat insulating material 32 which extends down the walls of conduit 30 as seen in Figures 1 and 4. A small tube or conduit 33 opens into conduit 30 and is connected to a box 34 which contains electrical connections for use when an electric heater is employed.

A suitable air cooler 35 is supported in the cover section immediately adjacent dry air outlet 36 and cools the air passing through said outlet.

The space between the inverted cover 27 and the bottom of casing 18 is large and forms a lower plenum chamber 37 in which the fan motor and fans are located. The fan motor 38 is arranged centrally of the chamber 37 and an intake blower or fan 39 and an exhaust blower or fan 40 are arranged at either end of motor 38 and are driven thereby. The blowers are preferably of the axial intake, peripheral exhaust type. An inlet conduit 41 extends from a point outside of the casing 18 to the axial intake of the blower 39, the blower exhausting into the lower plenum chamber 37 which is filled with air or gas under pressure of blower 39. A conduit 42 connects the interior of exhaust chamber 26 with the intake of exhaust blower 40 which exhausts into conduit 43 extending out of the casing 18. A door 44 is removably secured to an opening in casing 18 and may be removed to give access to the plenum chamber 37 and the blowers and motor.

Valve sleeve 18 is provided with large substantially semi-circular ports 45 adjacent its top which open into the cover section 28 the interior of which forms an upper plenum chamber, and the open top of the sleeve communicates with the interior of conduit 30. The lower end of the valve sleeve is provided with similar ports 46 which open into the exhaust chamber 26. The connections between valve sleeve 18 and conduit 30, plates 19, beds 20 and inverted cover 27 are air tight.

The valve sleeve is provided with an annular series of ports 47 of a number corresponding to the number of adsorbing sectors, each port 47 opening into one of the sectors above the adsorbent beds 20, as seen in Figure 3. A similar annular series of ports 48 open into the sectors below the adsorbent beds 20, as indicated in Figure 5. The lower end of the valve sleeve opens into lower plenum chamber 37.

A rotary, tubular valve body 49 fits snugly within the valve sleeve or casing 18 and is provided with a vertical central web or partition 50 dividing the valve body vertically into halves. A horizontal partition 51 completely blocks the interior of the valve body at the central portion thereof, at a point which coincides with the center of the adsorbent beds 20.

The adsorbing side of the valve body is closed at its top by a semi-circular horizontal web 52 extending from the vertical partition 50 to the side walls of the valve 49, while the opposite or reactivating side of the valve is closed at its

lower end by a horizontal web 53, as shown in Figures 1 and 7. A vertical radial partition 54 extends from the vertical partition 50 to the outer wall of the valve from the lower web 53 to the central horizontal partition 51, and when eight sectors are employed, the radial partition will extend at an angle of 45° from the partition 50 to form a purging duct in the lower half of the valve, the upper end of which is closed by partition 51, and the lower end of which opens into lower plenum chamber 37.

By reference to Figures 1, 4, 5 and 6 it will be seen that in a unit having eight sectors, the lower portion of the valve is divided into three chambers or ducts, namely an adsorbent duct 15 extending through an arc of 180°, a reactivating duct extending through an arc of 135°, and a purging duct extending through an arc of 45°. The lower adsorbent and purging ducts are open at their lower ends and closed at their upper 20 ends while the lower reactivating duct is closed at top and bottom. The upper half of the valve 25 is divided into two ducts or chambers of 180° each, the adsorbent duct being closed at its top while the reactivating duct is open at its top, communicating with conduit 30.

The upper adsorbent side of the valve is provided with a large port 55 extending from the top of casing port 45 to the bottom of casing ports 47 and through an arc of substantially 180°. At 30 any one time, port 55 is adapted to connect four of the upper portions of the adsorbent sectors to the upper plenum chamber. The reactivating side of the valve is provided with a port 56 extending from the top to the bottom of upper 35 casing ports 41 and through an arc of substantially 180°. The upper adsorbent duct is at all times in communication with the upper plenum chamber and out of communication with conduit 30 while the upper reactivating duct is at all 40 times in communication with conduit 38 and out of communication with the upper plenum chamber.

The lower adsorbent duct is provided with a port 57 extending from the top to the bottom 45 of lower casing ports 48 and through an arc of substantially 180°, while the purging duct is provided with a port 58 of a size and shape to correspond with one of the lower casing ports 48. The lower reactivating duct is provided with 50 a large port 59 extending from the top of casing ports 48 to the bottom of casing ports 46 and through an arc of substantially 135°. The lower adsorbent and purging ducts are at all times in communication with lower plenum chamber 37 55 and out of communication with exhaust chamber 26 while the lower reactivating duct is at all times in communication with exhaust chamber 26 and out of communication with lower plenum chamber 37.

The valve 49 is provided with a depending centrally arranged stub shaft 60 which fits into a hollow sleeve 61 carried by a support 62 straddling the blower motor 38 and secured to the bottom of casing 18. A suitable bearing, such as 65 a freely rotating ball 63, is arranged in the sleeve 61 and supports the shaft 60, permitting rotation thereof. A relatively large gear wheel 64 is removably mounted on shaft 60 to turn therewith, and engages a pinion 65 rotated by a small 70 electric motor 66 mounted on support 62. A small cooling fan 67 may be operated by motor 66 to cool the motor.

In operation, motor 38 operates blowers 39 and 40 and valve motor 66 rotates valve 49 at a slow 75

rate of speed. Air or other gas or fluid is drawn in through inlet 41 from some suitable source such as the room in which the apparatus is located, and forced into plenum chamber 37 under pressure of intake blower 39. Air under pressure of blower 39 passes into the open lower end of the lower adsorbent duct and through valve port 51 and casing ports 48 into the lower chambers 24 of four of the sectors, passing through the adsorbent beds 20 therein which remove all moisture from the air, and out through casing ports 47 and valve port 55 into the upper plenum chamber. The heat of adsorption is removed by cooler 35 as the dried air passes out through the outlet 36.

The exhaust blower 40 draws air from the room or other source down through conduit 30 where it is heated by heater 31, into the upper reactivating valve duct, through valve port 56 and casing ports 47 into the upper chambers 23 of three of the sectors, through the adsorbent beds 20 therein, and through casing ports 48 and valve port 59 into exhaust chamber 26 where it passes through conduit 42 to outlet 43 which discharges the reactivating air exteriorly of the room, or anywhere desired.

Purging air enters the lower end of the purging valve duct from lower plenum chamber 37 and passes through valve port 58 and one of the casing ports 48 into one of the sectors, through the bed 20 of adsorbent material therein and through one of the upper casing ports 47 into the upper reactivating duct where it joins the heated reactivating air, and is then used in reactivating, thereby utilizing the heat taken up by the purging air.

The valve partitions 50, 51 and 54 may be lined with some suitable heat insulating material such as asbestos to prevent transfer of heat from one duct to either of the other ducts, and suitable rings 68 of packing may be provided on the surface of valve 49 to prevent the passage of air.

The passage of air through the valve and adsorbent unit will be clear from an inspection of Figures 5 and 7. In Figure 7 the path of the air to be dried is indicated by arrows 69, while the path of the purging air is shown by arrows 70 and the path of the reactivating air is shown by arrows 71. It will be noted that the air to be dried and the purging air is taken from the same source and passes upwardly through the unit. The reactivating air passes downwardly through the unit, and the purging air joins the reactivating air in the upper reactivating duct 55 and then reverses its direction and passes downward with the reactivating air. The air to be dried gives up its moisture to the adsorbent beds, and is then cooled and passed through outlet 36. As each bed nears the point of saturation, it 60 goes into the reactivating phase of operation in which heated air removes the contained moisture and reactivates the adsorbent bed. At the end of the reactivating phase, the adsorbent bed is cooled by the purging air and vapors or products of combustion, when oil or gas heaters are used, are removed by the purging air.

The casing ports and valve ports are so spaced that as the sectors pass from adsorbing to reactivating to purging, there is no overlapping of operations and no admixture of the air from the different phases of operation. The valve is rotated at the desired speed by the motor 66. Assuming a speed of one complete revolution in sixteen minutes, and eight unit sectors, each sector is in the adsorbing phase for eight minutes,

the reactivating phase for six minutes and the purging phase for two minutes. The valve is rotated continuously, and every two minutes one sector is picked up and one sector dropped by the adsorbing phase, one sector is picked up and one dropped by the reactivating phase, and the sector just purged is the one picked up by the adsorbing phase while the sector just dropped by the reactivating phase is the sector to be purged for the next two minutes.

The operation is continuous, the only moving parts being the blowers and the valve which operate continuously. The heater operates continuously, thereby dispensing with complicated timing apparatus. A continuous flow of dried air issues from outlet 36. The adsorbing operation generates heat which is removed from the dried air by cooler 35. Due to the fact that the air entering the upper plenum chamber is a mixture from four sectors in different stages of the adsorbent phase, the temperature of the air in the upper plenum chamber is the average of the temperature of the air in the four sectors and is therefore much lower than the peak temperature attained near the end of the adsorbent phase in any one of the sectors. Consequently, a smaller cooler may be employed than is customary as it need not be of a capacity to cope with the peak temperature attained in the sectors.

An important feature of the present invention is the fact that the streams of air for adsorbing, reactivating and purging are continuous and uninterrupted. The air for purging passes through the unit in the same direction as the air for adsorbing and does not come into contact with the parts heated by the reactivating air. The operation of the blowers and heater is continuous and uninterrupted, the valve operation is also continuous and timed to move each sector into reactivation as its bed becomes saturated. The apparatus is compact and, due to the absence of many moving parts and timing and regulating devices, may be made very cheaply. The parts are accessible through the casing cover section 28 and door 44, and the entire adsorbing unit can be removed for inspection, repairs or replacement.

It is important that the purging air pass through the adsorbent beds in the same direction 50 as the air to be dried. The purging air is usually atmospheric air and consequently contains moisture. As it enters and cools the adsorbent bed, the adsorbent will extract some of the moisture at the point of entrance of the purging air. 55 If the air to be dried were passed through the beds in the opposite direction from that of the purging air, it would pick up some of this moisture as it left the bed, and as a consequence the air leaving the apparatus would not be so dry as air which left the bed through adsorbent in which no moisture had been left by the purging air. By passing the air to be dried through the adsorbent beds in the same direction as that taken by the purging air, the dried air leaves 60 the adsorbent through the portion of the bed in which no moisture has been left by the purging air.

The invention has been shown as having eight sectors for the purpose of illustration only, and 70 any other desired number of sectors may be employed. While the invention is particularly well adapted to the conditioning or de-humidification of air or gas, it may obviously be used for other purposes.

While the preferred embodiment of the invention has been shown and described, it is to be understood that various changes in the size, shape and arrangement of parts may be resorted to without departing from the spirit of the invention or the scope of the subjoined claims.

Having thus described our invention, what we claim and desire to protect by Letters Patent is:

1. In an adsorbent apparatus, a casing, an adsorbent unit arranged in said casing and comprising a plurality of adsorbent beds, said casing having a lower plenum chamber below the adsorbent unit and an upper plenum chamber above the adsorbent unit, a valve casing in said unit in communication with each of the adsorbent beds, said valve casing being in communication with both plenum chambers, a reactivating fluid inlet conduit in communication with the valve casing and out of communication with the plenum chambers, a reactivating fluid outlet conduit connecting the valve casing with the exterior of the casing and being out of communication with the plenum chambers, a valve in said valve casing having an adsorbing duct connecting the plenum chambers through a plurality of the adsorbent beds, said valve having a reactivating duct connecting the reactivating fluid inlet conduit with the reactivating fluid outlet conduit through other of said adsorbent beds, means to pass fluid through the adsorbing valve duct, means to pass a reactivating fluid through the reactivating valve duct, and means to operate said valve to successively add adsorbent beds to the adsorbent phase of operation while dropping other adsorbent beds therefrom, and to add adsorbent beds to the reactivating phase of operation while dropping other adsorbent beds therefrom.
2. In an adsorbent apparatus, a casing, an adsorbent unit arranged in said casing and comprising a plurality of adsorbent beds, said casing having a lower plenum chamber below the adsorbent unit and an upper plenum chamber above the adsorbent unit, a valve casing in said unit in communication with each of the adsorbent beds, said valve casing being in communication with both plenum chambers, a reactivating fluid inlet conduit in communication with the valve casing and out of communication with the plenum chambers, a reactivating fluid outlet conduit connecting the valve casing with the exterior of the casing and being out of communication with the plenum chambers, a valve in said valve casing having an adsorbing duct connecting the plenum chambers through a plurality of the adsorbent beds, said valve having a reactivating duct connecting the reactivating fluid inlet conduit with the reactivating fluid outlet conduit through other of said adsorbent beds, means to pass fluid through the adsorbing valve duct, means to pass a reactivating fluid through the reactivating valve duct, and means to operate said valve to successively add adsorbent beds to the adsorbent phase of operation while dropping other adsorbent beds therefrom, and to add adsorbent beds to the reactivating phase of operation while dropping other adsorbent beds therefrom.
3. In an adsorbent apparatus, a casing, an adsorbent unit arranged in said casing and comprising a plurality of adsorbent beds, said casing having a lower plenum chamber below the adsorbent unit and an upper plenum chamber above the adsorbent unit, a valve casing in said unit in communication with each of the adsorbent beds, said valve casing being in communication with both plenum chambers, a reactivating fluid inlet conduit in communication with the valve casing and out of communication with the plenum chambers, a reactivating fluid outlet conduit connecting the valve casing with the exterior of the casing and being out of communication with the plenum chambers, a valve in said valve casing having an adsorbing duct connecting the plenum chambers through a plurality of the adsorbent beds, said valve having a reactivating duct connecting the reactivating fluid inlet conduit with the reactivating fluid outlet conduit through other of said adsorbent beds, means to pass fluid through the adsorbing valve duct, means to pass a reactivating fluid through the reactivating valve duct, and means to operate said valve to successively add adsorbent beds to the adsorbent phase of operation while dropping other adsorbent beds therefrom, and to add adsorbent beds to the reactivating phase of operation while dropping other adsorbent beds therefrom, said valve having a purging duct connecting one of the plenum chambers to the reactivating duct through one of the adsorbent beds.
4. In an adsorbent apparatus, a casing having a fluid inlet and a reactivating fluid outlet, an adsorbent unit arranged therein and comprising a plurality of beds of adsorbent material, said unit being spaced from the bottom of the casing to form a lower plenum chamber, said casing extending above the adsorbent unit to form an upper plenum chamber, an intake blower adapted to force fluid under pressure into one of said plenum chambers, a valve casing extending between said beds of adsorbent material and communicating therewith and with said plenum chambers, a reactivating fluid conduit communicating with said valve casing, a reactivating blower connected to said valve casing, a valve arranged in said valve casing and having ducts and ports to connect the plenum chambers through a plurality of the adsorbent beds and to connect the reactivating fluid conduit to the casing reactivating fluid outlet through a plurality of the adsorbent beds, and means to rotate the valve.
5. In an adsorbent apparatus, a casing having a fluid inlet and a reactivating fluid outlet, an adsorbent unit arranged therein and comprising a plurality of beds of adsorbent material, said unit being spaced from the bottom of the casing to form a lower plenum chamber, said casing extending above the adsorbent unit to form an upper plenum chamber, an intake blower adapted to force fluid under pressure into one of said plenum chambers, a valve casing extending between said beds of adsorbent material and communicating therewith and with said plenum chambers, a reactivating fluid conduit communicating with said valve casing, a reactivating blower connected to said valve casing, a valve arranged in said valve casing and having ducts and ports to connect the plenum chambers through a plurality of the adsorbent beds and to connect the reactivating fluid conduit to the casing reactivating fluid outlet through a plurality of the adsorbent beds, means to rotate the valve, the rotation of said valve being continuous, and a continuously operated heater in the reactivating fluid conduit.
6. In an adsorbent apparatus, a casing, an adsorbent unit arranged in said casing and comprising a plurality of adsorbent beds, said casing having a lower plenum chamber below the adsorbent unit and an upper plenum chamber above the adsorbent unit, a valve casing in said unit in communication with each of the adsorbent beds, said valve casing being in communication with both plenum chambers, a reactivating fluid inlet conduit in communication with the valve casing and out of communication with the plenum chambers, a reactivating fluid outlet conduit connecting the valve casing with the exterior of the casing and being out of communication with the plenum chambers, a valve in said valve casing having an adsorbing duct connecting the plenum chambers through a plurality of the adsorbent beds, means to pass fluid through the adsorbing valve duct, means to pass a reactivating fluid through the reactivating valve duct, and means to operate said valve to successively add adsorbent beds to the adsorbent phase of operation while dropping other adsorbent beds therefrom, and to add adsorbent beds to the reactivating phase of operation while dropping other adsorbent beds therefrom.

above the adsorbent unit, a valve casing extending completely through the adsorbent unit and communicating with each of the adsorbent beds and with both plenum chambers, a reactivating fluid inlet conduit in communication with the valve casing and out of communication with the plenum chambers, a reactivating fluid outlet conduit connecting the valve casing with the exterior of the casing and being out of communication with the plenum chambers, a valve in said valve casing having an adsorbing duct connecting the plenum chambers through a plurality of the adsorbent beds, said valve having a reactivating duct connecting the reactivating fluid inlet conduit with the reactivating fluid outlet conduit through other of said adsorbent beds, and said valve having a purging duct connecting one of the plenum chambers to the reactivating duct through one of the adsorbing beds, means to force fluid in the last named plenum chamber and through the adsorbing and purging ducts, means to pass a reactivating fluid through the reactivating ducts, and means to operate said valve to successively add adsorbent beds to the adsorbent phase of operation while dropping other adsorbent beds therefrom, and to add adsorbent beds to the reactivating phase of operation while dropping other adsorbent beds therefrom.

5 disposed in alignment with the adsorbent beds and a longitudinal partition, means to pass a stream of fluid to be treated through the pipe and adsorbent beds on one side of the longitudinal partition, means to pass a reactivating fluid through the pipe and adsorbent beds on the other side of the longitudinal partition, and means to rotate the valve mechanism.

9. An adsorbent apparatus comprising a stationary casing, a pipe extending longitudinally through the casing substantially centrally thereof, partitions extending radially from said pipe to said casing and dividing the casing into a plurality of sectors, a bed of adsorbent material in each sector connecting the pipe and casing between the partitions, said pipe having slots disposed between adjacent partitions on each side of the adsorbent beds to connect the interior of the pipe with each sector on both sides of the adsorbent beds, a valve mechanism arranged in the pipe and comprising a transverse partition disposed in alignment with the adsorbent beds and a longitudinal partition, means to force a fluid under pressure through the pipe and adsorbent beds on one side of the longitudinal partition, means to draw a reactivating fluid by suction through the pipe and adsorbent beds on the other side of said longitudinal partition, and means to rotate said valve mechanism.

10. An adsorbent apparatus comprising a stationary casing, a pipe extending longitudinally through the casing substantially centrally thereof, partitions extending radially from said pipe to said casing and dividing the casing into a plurality of sectors, a bed of adsorbent material in each sector connecting the pipe and casing between the partitions, said pipe having slots disposed between adjacent partitions on each side of the adsorbent beds to connect the interior of the pipe with each sector on both sides of the adsorbent beds, a valve mechanism arranged in the pipe and comprising a transverse partition disposed in alignment with the adsorbent beds and a longitudinal partition, means to force a fluid under pressure through the pipe and adsorbent beds on one side of the longitudinal partition, means to draw a reactivating fluid by suction through the pipe and adsorbent beds on the other side of said longitudinal partition, and means to rotate said valve mechanism.

7. In an adsorbent apparatus having a plurality of stationary beds of adsorbent material disposed about a substantially central duct and communicating therewith, there being a rotatable valve mechanism in said duct, the method of adsorbing and reactivating which comprises forcing a fluid to be treated under pressure through said duct and valve mechanism, and drawing a stream of reactivating fluid by suction through said duct and valve mechanism, whereby any leakage of fluid will be from the fluid to be treated to the stream of reactivating fluid.

8. An adsorbent apparatus comprising a stationary casing, a pipe extending longitudinally through the casing substantially centrally thereof, partitions extending radially from said pipe to said casing and dividing the casing into a plurality of sectors, a bed of adsorbent material in each sector connecting the pipe and casing between the partitions, said pipe having slots disposed between adjacent partitions on each side of the adsorbent beds to connect the interior of the pipe with each sector on both sides of the adsorbent beds, a valve mechanism arranged in the pipe and comprising a transverse partition disposed in alignment with the adsorbent beds and a longitudinal partition, a stationary chamber in communication with the pipe on one side of the longitudinal partition and connected to a source of fluid supply, a stationary reactivating fluid duct in communication with the pipe on the other side of the longitudinal partition, and means to rotate the valve mechanism.
